PINBALL GAME BOARD

Clifton L. Johnson, 147 S. Ridge Road,
San Francisco, Calif.

Filed Mar. 30, 1964, Ser. No. 79,257

Term of patent 14 years

(Cl. D34—5)

FIG. 1.

FIG. 2.

The dominant features of my design reside in the portions shown in full lines.

I claim:

The ornamental design for a pinball game board, as shown and described.
